United States Patent Office

Des. 210,849

Patented Apr. 23, 1968

210,849

SYMBOL GUIDE

Donald E. Froemming, Brookfield, Wis., assignor to
Racine Hydraulics, Inc., a corporation of Wisconsin

Filed Oct. 17, 1967, Ser. No. 9,025

Term of patent 14 years

(Cl. D52—6)

FIG. 1.

FIG. 2.

FIG. 1 is a plan view of the symbol guide embodying my invention; and

FIG. 2 is a vertical section on an enlarged scale taken generally along the line 2—2 in FIG. 1.

I claim:

The ornamental design for a symbol guide, as shown.
